UNITED STATES PATENT OFFICE.

THEODORE BOLLIN, OF OKMULGEE, OKLAHOMA.

ELECTRICAL MASSAGE APPARATUS.

1,240,410.

Specification of Letters Patent. Patented Sept. 18, 1917.

Application filed April 25, 1916. Serial No. 93,424.

To all whom it may concern:

Be it known that I, THEODORE BOLLIN, a citizen of the United States, residing at Okmulgee, in the county of Okmulgee and State of Oklahoma, have invented certain new and useful Improvements in Electrical Massage Apparatus, of which the following is a specification.

My invention relates to new and useful improvements in medical appliances the primary object of my invention being the provision of an electrical massage device which is intended particularly for the treatment and curing of cases of chronic constipation and chronic diarrhea, the same apparatus being employed for either purpose but in a different manner.

More specifically, my invention consists in the provision of a device having a suitable abdominal supporting portion and a plurality of massage rollers capable of being driven in a circular path, in either direction, one of the massage rollers being provided with a current conducting surface. My apparatus further includes a rectal electrode which, with the conductor covered roller, form the electrodes of a faradic circuit, suitable means being provided for supplying proper current to the rectal electrode and for conducting current, passing from this electrode through the body of the patient from the conductive covering of the roller electrode the former electrode constituting the positive electrode and the latter the negative electrode of the circuit.

One of the primary objects of my invention consists in the provision of a suitable body to which the abdominal supporting device is connected and which carries certain of the massage rollers, including that having the conductive coating, this body being so formed and arranged that it may be interchangeably employed either with a cabinet form of apparatus or with a portable hand apparatus as preferred.

In this connection, a further object of my invention consists in the provision of a novel and efficient form of cabinet apparatus including a revolvably supported disk which may be driven by a hand crank or other suitable means and to which the body carrying the abdominal support and massage rollers may be connected, the cabinet also providing additional support for the patient's abdomen when the device is in use.

Another object along this line consists in

providing a stand or bracket upon which the cabinet may be supported at variable heights in order that a patient may perform self treatment if desired while standing in an erect position, the cabinet device ordinarily being employed by doctors or nurses with the patient in a reclining position.

In this connection also, another object of my invention consists in the provision of a portable device or structure upon which the massage roller carrying body may be mounted and which provides means for rotating such body to drive its rollers when in use.

With these and other objects in view, my invention will be fully described, illustrated in the accompanying drawings and then specifically pointed out in the claims, which are attached to and form a part of this application.

Figure 1 is a top plan view of the cabinet form of my improved medical appliance, the cover being removed to show the device itself.

Fig. 2 is a vertical central sectional view taken through the device, a portion of the front wall however, being shown in elevation.

Fig. 3 is a sectional view at right angles to that shown in Fig. 2.

Fig. 4 is a sectional view of the massage roller having the conductive covering or sleeve,

Fig. 4^a is a perspective view of a modified form of electrode forming massage roller.

Fig. 5 is a perspective view of the bracket for supporting the electrode forming roller,

Fig. 6 is a perspective view of the rectal electrode,

Fig. 7 is a longitudinal sectional view of the rectal electrode,

Fig. 8 is a perspective view of my improved cabinet form of appliance mounted upon its stand,

Fig. 9 is a rear elevation of the portable form of apparatus,

Fig. 10 is a central longitudinal sectional view of the form shown in Fig. 9, parts being broken away to permit its showing upon an enlarged scale.

As previously mentioned, my apparatus comprises an electrode and massage carrying body which may be interchangeably connected either to a cabinet form of driving mechanism or to a portable driving mechanism but for the sake of convenience, I

would first like to describe it in connection with the cabinet form of structure. Referring to Figs. 1, 2, and 3 of the drawings, 10 indicates a cabinet which is substantially 5 square in shape being formed of wood or other suitable material and including a bottom 11, side and end walls 12 and a cover 13 having a peripheral flange 14 encircling the cabinet when the cover is in place and adapted to receive the locking studs 15 of hinged latches 16 carried by the walls 12. The front wall of this cabinet is formed with openings to receive drawers 17 which are separated by a partition 18, one of these 10 drawers generally containing the electric apparatus of the device such as one or more dry cells and a generator and the other any cloths, bandages or other articles which may be employed in the treatment. The cabinet 15 immediately above the drawers is provided with a horizontal partition furnishing a false bottom 19 which supports the mechanism proper of the appliance. Brackets 20 of any suitable type are secured at intervals 20 to the inner faces of the walls of the cabinet and support an inwardly directed peripheral ledge 21 which carries a top 22 preferably formed of vulcanite or other suitable non-current conducting material of such a nature that it will not warp or change 25 its shape or proportion due to changes in temperature or moisture. The upper face of this top or in effect table 22 lies flush with the upper edge of the cabinet and is formed 30 with a central opening 23, preferably circular in shape and slightly less in diameter than the transverse dimension of the cabinet.

The partition 18 is formed centrally with an opening to receive the enlarged head 24 of the supporting shaft 25 which extends through the false bottom 19 and which, at its upper end, is reduced and screw threaded, as shown at 26. A sleeve 27 surrounds this shaft 25 resting at its upper end in the plane 45 of the shoulder formed by reducing the shaft. A beveled gear 28 is formed centrally with an annular groove to form a ball race for bearings 29 which engage the upper end of the sleeve 27 and with an opening to 50 receive the threaded sleeve of a cap screw 30 which is fixed upon the threaded end of the shaft 25. This cap screw has a flanged head 31 and a relatively heavy disk 32 of copper is held between the flange of the cap screw 55 and the gear 28, projecting peripherally beyond the gear.

One side wall of the cabinet is provided with a bearing 33 to receive a shaft 34 which at its outer end is provided with a removable hand crank 35. The inner end of this shaft is journaled in the upstanding arms 36 and the upstanding arm 37 of a bracket 38 secured to the false bottom 19 and between one of the arms 36 and the arm 37 carries a beveled pinion 40 which meshes with the

beveled gear 28. The bracket may be fastened to the false bottom by bolts 41 or other suitable means and the arms 36 project above the bracket and receive the trunnions 42 of a spherical roller bearing 43 which supports 70 the disk 32. At spaced intervals about the gear 28, I provide additional brackets identical in construction with the bracket 38 and each having a shaft 44 carrying a beveled pinion 45 meshing with the gear and each receiving the trunnions of a bearing 46 supporting the disk 32. By this means, the disk is firmly supported for rotation about the shaft 25 and yet held against disengagement therefrom, the crank 35 serving as 80 a means for imparting movement to the disk in either direction.

Secured to the upper face of the disk 32 and at diametrically opposite sides thereof, are segmental body members 47 having their 85 chordal edges extending in parallel spaced relation. These body members may be secured to the disk by bolts 48 or in any other suitable manner and interposed between them and resting upon the intermediate portion of the disk 32 is the main body member 49 which is detachable from the disk and which with the segmental body members 47 makes up a complete rotating disk which as will be later explained, carries the massage 95 elements or rollers of the apparatus. This intermediate body member 49 is formed in its lower face with threaded sockets to receive the threaded ends of dowel pins 50, the projecting ends of which pass through 100 openings formed in the disk 32 and into sockets formed in the upper face of the gear 28 to lock the intermediate body member against sliding movement between the segmental body members and to lock the disk 32 105 to the gear 28 so that rotation of the gear will cause rotation of the disk and consequently, the rotation of the massage carrying support 51 made up of the various body members 47 and 49.

These body members 47 and 49 are formed of vulcanite or other equivalent material and the lower face of the intermediate body member 49 is provided with a radially extending channel to seat a conductor strip 52 115 of copper which is secured in its seat by any suitable means and which when the intermediate body member is in place engages the copper disk 32 in order that current to the sleeve 18 may pass to the strip 52. 120

The end portions of the intermediate body member 49 are provided with alined radially extending slots 53 one of which communicates with a corresponding slot 54 formed in the strip 52. In like manner, the segmental shaped body members 47 are provided at diametrically opposite points with alined radially extending slots 55 extending at right angles to the slots 53, these various slots being each spaced at a distance 130

of substantially 90° from adjacent slots. U-shaped brackets 56 engage by their intermediate portions upon the upper face of the massage element carrying member 51, such portions extending radially of the member and over the slots therein, and clamping bolts 57 are passed through the intermediate portions of the brackets and through the slots and provided with thumb nuts 58 by means of which the brackets may be clamped in place. Obviously, because of this arrangement, the brackets may be adjustably clamped to the supporting member 51 at a more or less distance from the center thereof as desired. The upstanding arms of all of the brackets 56 save that which is clamped through the slot communicating with the slot of the conductor strip 52 are provided with horizontally aligned openings to journal the trunnions 59 of spherical massage elements 60 which are thus rotatably mounted in the brackets and which, as shown project somewhat above the substantially annular table 22, the cover being internally recessed as shown at 61 to fit over them. The remaining bracket 56 is identical in construction with those previously described except that while one upstanding arm is formed with an opening 62, its other arm is formed with a vertical slot 63 opening through its free end. Because of this, the trunnions 64 of a combined massage roller and electrode 65 may be removably supported by the bracket. A leaf spring 66 is fixed at one end to the slotted arm of the bracket and formed at its opposite end with an opening 67 to receive the adjacent trunnion of the roller 65 and lock it against outward movement from the slot 63, the intermediate portion of this spring being outwardly bowed to facilitate its application or removal from such trunnion. This combined massage roller and electrode 65, as best shown in Fig. 4 of the drawings, has its body constructed of vulcanite, vulcanized rubber or other suitable non-conducting material. This body is in the form of a sphere and is mounted upon a diametrically extending shaft 68 upon the ends of which are formed the trunnions 64 and the face of the body member 65 in a diametric plane at right angles to the shaft 68 is grooved or channeled as shown at 69 to seat a sleeve or ring 70 of copper or other suitable electrical conductor which is secured in place in the channel and in electrical connection with the shaft 68 by means of one or more locking screws 71. It should be noted that the outer face of this conductor ring is flush with and forms a continuation of the face of the massage roller 65. The other rollers are all formed of non-conducting material and are none of them provided with any conductor ring. Obviously, current may pass from the positive electrode, to be later explained, through the body of a patient to the conductor ring 70, from this ring to the bracket 56, strip 52 and through the disk 32 to the sleeve 18 and so back to the battery or other source of energy. Preferably, a combined cut-out switch and rheostat 72 is interposed in the circuit in order that the current may be shut off or turned on as desired and its strength properly regulated.

The intermediate body member 49 is formed centrally with an opening to receive the cap nut 31 by means of which the disk 32 and gear 28 are held against displacement from the shaft 25 and surrounding this opening, the upper face of the body member 49 is formed with concentrically disposed annular seats 73 and 74 and with a ball race 75 in these seats. The shank portion 76 of an abdominal support 77 engages against the inner seat 73 and is formed with a peripheral flange 78 resting upon the ball bearings 79 in the bearing race 75 and projecting over the seat 74, a sectional retaining ring 80 secured by screws or other fastening devices 81 serving to prevent disengagement from the support 77. The lower end of the shank 76 is formed with a semi-spherical socket 82 and the upper face of the cap nut 31 is formed with a concavity to receive a single ball bearing 83 which engages the socket 82 and additionally journals the abdominal support 77. Obviously, the abdominal support 77 is therefore mounted in such a manner that it may be held against turning while the massage element supporting member 51 is rotated by the crank 55. The body proper of the abdominal support 77 is cup-shaped as shown at 84 with its free edge disposed at a level slightly below the upper peripheries of the massage elements 60 and this cup-shaped body is formed interiorly with a protuberance which forms an abdominal engaging portion of the support.

Cooperating with the above described portion of my medical appliance, is a positive rectal electrode best shown in Figs. 6 and 7 and indicated as a whole by the numeral 86. This electrode is made up of two substantially cylindrical body members 87 and 88 formed of vulcanized rubber or other suitable non-conducting material, the body members being so shaped and proportioned that when the electrode is assembled, it tapers somewhat from end to end. A contact disk 89 of copper or other suitable current conducting material is provided centrally with a threaded stud 90 which engages in a threaded socket formed in the larger end of the body member 88 and the members 87 and 88 are connected by means of a rod 91 of any suitable current conducting metal which is passed axially through the body member 87 and is threaded into the socket formed in the disk 89 and its stud 90 the rod 91

91 at its outer end being enlarged to provide a binding post 92 by means of which a covered conducting wire may be attached. The body member 87 is provided with a peripheral flange 93 which covers the rear face of the conductor disk 89 and which is extended to engage about the peripheral edge of such disk. The body portion 88 of the rectal electrode 87 is so shaped and proportioned 10 that it may be inserted in the rectum of the patient and for this reason is provided with an annular enlargement or bulge 94 intermediate its length in order that it may be readily held in place within the rectum 15 with the contact plate 89 in snug engagement with the sphincter muscle of the rectum.

With the cabinet form of electrical massage instrument above described, the treatment of the patient is as follows: The patient's colon may be first emptied by any suitable enema and with the cabinet positioned upon a bed or operating table, the patient is placed with the abdomen resting 25 upon the abdominal support 77 and table 22. The positive electrode is then inserted in the patient's rectum and the massage element supporting member or disk 51 is continuously and steadily revolved by means of 30 the crank 35, current being turned on to the proper strength by means of the combined switch and rheostat 72. Preferably, the conductor ring 70 of the negative electrode and the exposed surface of the disk 89 of the 35 positive electrode are covered with cloths moistened in a salt solution in order to insure good contact and at the same time not have the current too sharp. When treating a patient for constipation, care should be 40 taken that the massage elements are turned from right to left in order that the negative electrode or roller may pass in a circular path over the patient's abdomen along the normal course of peristaltic motion of the intestines, creating such a motion of the intestines or intensifying this motion to accomplish 45 the desired result. It will therefore be seen that the massaging accomplished by my appliance tends to intensify proper muscular movement of the intestines or to cause such movement in case it is lacking and therefore operates to produce the desired result in the natural manner. Obviously, the same apparatus may be employed for 50 treatment of chronic cases of diarrhea by reversing the direction of rotation of the massage element carrying body in order that the massage elements may be rotated in a contra-peristaltic direction.

60 If desired, this cabinet form of appliance may be mounted upon a suitable stand to permit self treatment by a patient in upright or standing position. For this purpose, I have provided a stand of the type shown in Fig. 8 including a base or pedestal

95 having a vertical standard 96 from which extend opposite lateral branches 97 terminating in guide arms 98 projecting in parallel spaced relation to the standard 96. The bottom 11 of the cabinet is formed with a 70 plurality of guide loops 99 which receive the standard and its arms and the cabinet may be secured in adjusted vertical position upon the stand by a set screw 100. If desired, the upper end of the standard 96 may 75 be rebent as shown at 101 to support a winding drum 102 operable by a crank 103 and carrying a cord or cable 104 connected at its free end to the cabinet. Clearly, the method of treatment with the exception of 80 the position assumed by the patient will be the same with the cabinet supported as shown in Fig. 8.

At times, however, patients are so ill or feeble that they cannot be turned upon their 85 abdomens or cannot stand in an upright position and for this reason I have provided a portable form of apparatus which may be employed as a substitute for the cabinet form above described. Such a form of apparatus is clearly illustrated in Figs. 9 and 10 of the drawings and as therein shown, is adapted to interchangeably receive the intermediate body portion 49 carrying one of the massage rollers 60 and the electric massage roller 65 and abdominal supports 77, all of which have been described in connection with the cabinet form of the invention. This portable device includes a beveled gear 115 having threaded sockets to receive 100 screws 106 which are passed through openings 107 formed in the intermediate body portion or member 49 and through spacer blocks 109 interposed between the member 49 and the gear 105, the pins 50 seating in 105 sockets formed in the spacer blocks. A shaft 108 is formed at one end with a concavity 109 to receive the ball bearing 88 and at its opposite end with a split clamping sleeve 110 which may be secured by clamping bolts 111 about a shaft bearing or sleeve 112. A collar 113 is secured about the shaft 108 by a set screw 114 or other equivalent fastening device in order that the gear 105 may not become disengaged from the shaft about 115 which it is free to rotate. Beveled pinions 115 and 116 are mounted upon a shaft 117 extending through the sleeve 112 in which it is journaled, one of these pinions being fixed to the shaft by a set screw 118 or other suitable means and the other being idly mounted upon the shaft. A spacer sleeve 119 engages against the idly mounted beveled pinion 116 and is held against it by the cap nut 120 threaded upon one end of the shaft 117, the shaft therefore being held against longitudinal movement through the sleeve 112 by the fixed pinion 115 and cap nut 120. A second spacer sleeve 121 engages against the fixed pinion and is in turn 130

engaged by a handle forming sleeve 122 of insulating material such as vulcanized rubber or fiber. An additional spacer sleeve 123 engages against the other end of the handle forming sleeve 22 and engaging against this latter spacing sleeve is a beveled pinion 124 which is fixed to the shaft 117 by a set screw 125. A bracket 126 is provided at its ends with split clamping rings 127 which may be engaged about a bearing forming sleeve 128 by clamping screws 129. This sleeve 128 engages against the pinion 124 and is formed with a socket to receive one end of a shaft 130 which is rotatably journaled in the bracket 126 and held against longitudinal movement by a collar 131. This shaft 130 carries a beveled gear 132 which meshes with the disk 124 and at its free end carries a hand crank 133 by means of which it may be rotated to transmit power from the gear 132 to the pinion 124 and shaft 117 and so through the pinion 115 to the gear 105 and consequently to the massage roller and abdominal support carrying member 49.

The free end of the shaft 117 is provided with a peripheral groove or ball race 134 and a collar 135 surrounds such end of the shaft and with the groove receives ball bearings 135 which are locked in place by a cap nut 137 threaded into the end of the collar and which in turn lock the collar against disengagement from the shaft. This collar is provided with a threaded extension 138 about which is threaded one end of a handle 139 of any suitable non-conducting material such as vulcanized rubber. This handle is provided axially with a passage to receive a covered conducting wire 140 which, at its inner end, is connected by a binding post 142 to the collar 135. It will therefore be clear that current passing from the body of the patient to the conductor ring of the electrode forming roller 65 may pass to the copper strip 32, through one of the screws 106 to the beveled gear 105 and so to the beveled pinions 115 and 116 and along the shaft to the collar and wire 140.

It will of course be understood that the rectal electrode is employed in connection with the above described portable apparatus, the two electrodes being connected in circuit with a suitable source of faradic energy and that the portable device will be employed in the same manner as the cabinet form of the appliance with the exception that being portable, it may be readily applied to a patient in a normal reclining position. Either form of appliance may be employed for general massage purposes either with or without the discharge of current as preferred and the cabinet form of massage appliance may be employed for massage purposes with all four massage rollers or with only two, the intermediate body portion with its abdominal support and massage rollers being

removed from the remainder of the appliance in the latter case. Except in very severe cases of constipation, no enema should be employed and in any event, its use should be discontinued as soon as possible generally after the first or second treatments. Furthermore, in severe cases a combined galvanic and faradic current may be employed. In any event, it should be borne in mind that for treatment of constipation, the massage rollers must move in a circular path from the right to the left in order that the current supplied to the body may follow this path to escape.

Having thus described my invention, what I claim and desire to secure by Letters Patent is:

1. A massage instrument including a massage element adapted to conduct electricity from the body of the patient being massaged, means for driving the element in a circular path upon the patient, and an electrode adapted to be inserted in the rectum of the patient to form a supply conductor.

2. An electrical massage instrument including a rotatably mounted member, means for rotating the member, a support carried by the member and free to remain stationary during rotation of the member, massage elements carried by the member, means whereby one element may conduct current from a patient being treated when the patient is resting against the support, and means for supplying current to the patient.

3. An electrical massage instrument including a rotatably mounted member, means for rotating the member, a support carried by the member and free to remain stationary during rotation of the member, massage elements carried by the member, means whereby one massage element may conduct current from a patient being treated when the patient is resting against the support, and means for conducting current to the patient, said means including an electrode adapted to be inserted in the rectum of a patient and connected in circuit with the current conducting massage element.

4. An electrical massage apparatus including a shaft, a gear rotatable on the shaft, means for rotating the gear, a body member detachably connected to the gear to be driven thereby, a supporting member having swiveled connection with the body member and projecting therefrom, a plurality of massage elements peripherally spaced about the supporting member and carried by the body member, each massage element being in the form of a roller of non-conducting material and one of such rollers being provided with a partial covering of conductive material in electrical circuit with the shaft, a cabinet structure surrounding and inclosing the above mechanism, a table forming a portion of the cabinet structure and par-

tially closing the top thereof, said table being formed with an opening through which the massage elements and supporting member project, and means connected in circuit 5 with the shaft for conducting away current conducted to the body of a patient being operated upon by that massage element in electrical connection with the shaft.

5. An electrical massage apparatus including a shaft, a gear rotatable on the shaft, means for rotating the gear, a body member detachably connected to the gear to be driven thereby, a supporting member having swiveled connection with the body member and projecting therefrom, a plurality of massage elements peripherally spaced about the supporting member and carried by the body member, each massage element being in the form of a roller of non-conducting material and one of such rollers being provided with a partial covering of conductive material in electrical circuit with the shaft, a cabinet structure surrounding and inclosing the above mechanism, a table 20 forming a portion of the cabinet structure and partially closing the top thereof, said table being formed with an opening through which the massage elements and supporting member project, and means connected in circuit with the shaft for conducting current supplied by that massage element in electrical connection with the shaft from the body of a patient being operated upon, said means including an electrode adapted 35 to be inserted in the rectum of the patient.

6. An electrical massage instrument including a positive electrode applicable to the body of a patient being treated, a rotatably mounted member, means for rotating the

member, a massage element carried by the member at a point spaced from its center of rotation and constituting a negative electrode, and patient engaging means carried by the member and free to remain stationary while the member is driven. 40 45

7. An electrical massage instrument including a cabinet, a table supported within the upper portion of the cabinet, a member rotatably supported above the table, diametrically disposed massage elements mounted upon the member, a centrally located abdominal support having swiveled connection with the member, means within the cabinet for rotating the member, means for conducting current from one of the massage elements, and a rectal electrode for supplying current to a patient being massaged. 50 55

8. An electrical massage instrument including a rectal electrode of non-conducting material provided in its length with an angular abutment, a current conducting plate secured to the forward face of the abutment, means for supplying current to the plate, a massage element capable of conducting current from the body of a patient, and means 60 65 for driving the massage element in a circular path.

9. An electrical massage instrument including a rectal electrode for supplying current to the body of a patient being treated, 70 a massage roller adapted to conduct current from the body of the patient being treated, means for supporting the massage roller in engagement with the body of the patient to permit its rotation, and means for driving 75 the massage roller in a circular path.

In testimony whereof I affix my signature.
THEODORE BOLLIN. [L.S.]
